UNITED STATES PATENT OFFICE.

ABRAHAM L. KELLER, OF SPRINGFIELD, MASSACHUSETTS.

STEM WINDING AND SETTING WATCH.

SPECIFICATION forming part of Letters Patent No. 357,306, dated August 7, 1888.

Application filed November 8, 1886. Serial No. 218,343. (Model.)

To all whom it may concern:

Be it known that I, ABRAHAM L. KELLER, a citizen of the United States, residing at Springfield, in the county of Hampden and 5 State of Massachusetts, have invented a new and useful Improvement in Watches, of which the following is a specification.

My invention relates to improvements in watches in which a conical pin operates in 10 conjunction with a conical winding-stem and a shipping-plate, also provided with a conical pin, operating in conjunction with the spring-plate carrying the conical pin that operates in conjunction with the crown-stem; and the objects of my improvements are, first, to provide 15 a watch with stem-winding and hand-setting mechanism which shall be simple, durable, positive in action, and easily operated, and that it is intended for any pendant-winding 20 and hand-setting watch. I attain these objects by the mechanism illustrated in the accompanying drawings, in which—

Figure 1 is a plan of my mechanism in its normal position for winding. Fig. 2 is also a 25 plan showing the mechanism in position for setting the hands. Figs. 3, 4, and 5 are detail parts of the same.

Similar letters refer to similar parts throughout the several views.

The case is provided with a pendant, A, into 30 which is fitted a crown-stem, *h*, to which is secured the crown or knob *l*. The stem *h* has its inner end formed into a square to which is fitted the pinion *g*. Said pinion is held in its 35 place by a recess formed in the plate *B*, while the crown-stem is moved endwise, as herein-after described. The stem *h* is also provided with a conical-shaped portion, *o*, which has for its function to throw the hand-setting and 40 winding gears in and out of action by moving the crown-stem endwise. The vibrating-yoke *j* is pivoted upon the axis of the gear-wheel *a*. A spring, *m*, keeps this plate in its normal position, as shown in Fig. 1. When 45 in this position the winding-gears *b* and *f* are in mesh, and in this position the crown-stem is pushed in and is in its normal position, as shown in Figs. 1 and 3. The spring-plate *i* is provided with a conical pin, *p*, which operates in conjunction with the conical portion of 50 the crown-stem. Said spring-plate *i* has its

free end provided with an inclined surface *q*, which acts in conjunction with a conical pin, *n*, secured to the under side of the oscillating yoke *j*. When the crown-stem is pulled out, 55 the conical pin or stud *p* rests on the highest portion of the cone of the stem *h*, as shown in Fig. 4, and the inclined end of the spring-plate *i* has caused the vibrating yoke *j* to move forward until the gears *c* and *d* mesh, and thus 60 motion is communicated to the hand-arbor wheel *e* by rotating the crown-stem in either direction. When the hands have been adjusted, the crown-stem is pressed in and the conical stud *p* assumes a position, as shown in 65 Figs. 3 and 5. Simultaneous with this movement the conical stud *n* is also relieved, and spring *m* carries back the vibrating yoke *j* to its normal position, as shown in Figs. 1, 3, and 5. When in this position, the gears *c* and *d* 70 are out of action with the gear *e*, and gear *a* and *b* now communicate motion to the winding-gear *f* in the manner shown in Fig. 1. When the crown-stem is rotated, the spring *m* also acts as a safety-spring should the crown- 75 stem be revolved in the wrong direction. In this case the wheel *b* would lift itself out of gear with the gear *f*. In other words, the spring *m* is not strong enough to hold the gears *b* and *f* in mesh when the crown-stem is turned 80 in the wrong direction.

I preferably make the studs or pins *n* and *p* conical, so that they have a free and easy action in sliding over their respective surfaces. These points are hardened, and the whole action is thus very durable, yet simple.

Having thus fully described my invention, what I therefore desire to secure by Letters Patent is—

1. The combination, with the gears of the winding-drum and dial hand-arbor, of the vibrating yoke provided with the intermediate gears, and the spring-plate *i*, having an inclined end for connection with the conical pin on the yoke and spring *m*, and the crown stem 95 having both a rotary and longitudinal movement, and intermediate mechanism whereby the watch may be either wound or the hands adjusted, as set forth.

2. The combination, with the winding and 100 hand arbors, of the vibrating yoke pivoted concentric about the axis of gear *a* and pro-

vided with intermediate gears for engaging and disengaging with the gears upon said arbors, the spring-plate *i*, having an inclined surface, and the conical pin *n*, the spring *m*, 5 and the crown-stem provided with the conical surface and operating-pinion, all substantially in the manner and for the purpose set forth.

3. The vibrating yoke *j*, provided with a conical pin, *n*, and operating in conjunction 10 with the inclined end of the spring-plate *i*, whereby said yoke *j* is caused to vibrate for alternately winding and setting the watch, in

the manner substantially as shown and described.

4. The combination, substantially as hereinbefore set forth, of the crown-stem *h*, spring-plate *i*, oscillating gear-plate *j*, gear-wheels *a*, *b*, *c*, *d*, *e*, and *f*, all arranged to operate in the manner and for the purpose set forth. 15

ABRAHAM L. KELLER.
